Attorney

UNITED STATES PATENT OFFICE

DANIEL ADAMS, OF ANN ARBOR, MICHIGAN, ASSIGNOR TO LIBBEY-OWENS-FORD GLASS COMPANY, OF TOLEDO, OHIO, A CORPORATION OF OHIO

TABLE FOR SUPPORTING GLASS SHEETS AND METHOD OF BEDDING THE SAME THEREON

Application filed July 26, 1928. Serial No. 295,399.

This invention appertains to an improved type of table for supporting glass sheets to be surfaced and further to an improved method of laying or bedding the glass sheets thereon.

The present invention is primarily designed for and probably finds its greatest utility when incorporated in the continuous system for surfacing sheet glass although it is of course not necessarily restricted to such use. As is well understood, in the so-called continuous system for surfacing sheet glass, a plurality of tables are ordinarily coupled end to end and are adapted to carry the glass sheets laid or bedded thereon successively beneath and in contact with the grinding and polishing tools of a plurality of grinding and polishing units.

The aim and principal object of this invention is the provision of a novel type of table and an improved method of laying or bedding the glass sheets thereon, the employment of such a table and the practice of such method rendering possible the bedding of the glass sheets upon said table in a simple and efficient manner to the end that the said sheets will be rigidly and uniformly supported throughout and maintained in desired position against accidental displacement during the surfacing operation whereby the danger of breakage or the liability of the sheets cracking or becoming displaced will be eliminated or at least greatly minimized.

Other objects and advantages of the invention will become more apparent during the course of the following description when taken in connection with the accompanying drawings.

In the drawings forming a part of this application and wherein like numerals are employed to designate like parts throughout the same,

Fig. 1 is a perspective view of an improved type of table constructed in accordance with the present invention.

Fig. 2 is a section taken substantially on the line 2—2 of Fig. 1, and

Fig. 3 is a section taken substantially on the line 3—3 of Fig. 2.

The improved type of table herein pro-

vivid is designated in its entirety by the numeral 9 and consists of a base or body portion 10 mounted upon wheels 11 running upon rails or tracks 12, the body portion of the table being provided upon its upper surface with a plurality of spaced transversely arranged channels 13. Carried by the base or bottom portion of the table is a top or cover plate 14 secured thereto by means of a plurality of fastening elements 15. The top 14 of the table is provided with a plurality of spaced openings 16 communicating with the channels 13, said openings being properly distributed throughout the area of said table.

Resting upon the table top 14 is a preferably wire netting or screen 17 and stretched over this screen is a filter cloth 18 of any suitable material. Arranged around the edges of the table is a raised rim 19 secured in place by a plurality of fastening elements 20 which also pass downwardly through the top 14. The edges of the screen 17 and filter cloth 18 are adapted to be rigidly clamped between the rim 19 and table top 14 as shown.

The channels 13, provided in the body portion of the table, are closed at one end as by means of a plate or the like 21 while the opposite ends of said channels communicate with a longitudinally extending manifold 22 carried by the opposite side of the table and having one or more outlet pipes 23 associated therewith.

In accordance with the present invention, a suitable material or mixture, within which the sheet is to be embedded, is adapted to be deposited upon the table so as to rest upon the filter cloth 18. This material is herein designated by the numeral 24 and preferably consists of a mixture of sand and water of the desired consistency or density, although any other material or mixture found suitable for this purpose may be used without departing from the spirit of the invention. In practice, the mixture of sand and water or other material is adapted to be deposited upon the table so as to fill the entire space within the rim 19 and the said mixture is adapted to be on a level with the top thereof. After the mixture of sand and water

has been properly placed upon the table and levelled off, the glass sheet 25 to be surfaced is adapted to be laid thereon. When the glass sheet is laid upon the mixture of sand and water, the water will naturally gravitate or filter through the covering composed of the filter cloth 18 and screen 17, through the openings 16 into the channels 13 and exteriorly thereof through the manifold 22 and outlet pipe 23.

It will be readily apparent that as the water flows off from the mixture, the glass sheet will be permitted to settle down and become embedded within the remaining solid mass or sand which will form a cast or mold therefore. The sheet can then be passed beneath and subjected to the action of the grinding and polishing machines and due to the fact that the sand will rigidly and uniformly support the sheet throughout its entire area, the danger of said sheet cracking or becoming broken or accidentally displaced during the surfacing operation will be avoided or at least greatly minimized.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

I claim:

1. A table for supporting glass sheets to be surfaced including a base or body portion provided with a plurality of spaced channels, a top for the base or body portion provided with a plurality of openings communicating with the channels, a wire netting resting upon said top, a filter cloth stretched over the wire netting and adapted to receive thereon a material within which the sheet is to be embedded and permit the liquid contained in said material to pass through the wire netting and openings into the channels, and a raised rim arranged around the edge of the table, the edges of the wire netting and filter cloth being clamped between the rim and top.
2. A table for supporting glass sheets to be surfaced including a base or body portion provided with a plurality of spaced transversely arranged channels, a top for the base or body portion provided with a plurality of openings communicating with the channels, a wire netting resting upon said top, a filter cloth stretched over the wire netting and adapted to receive thereon a material within which the sheet is to be embedded and permit the liquid contained in said material to pass through the wire netting and openings into the channels, a raised rim arranged around the edges of the table, the edges of the wire netting and filter cloth being clamped between the rim and top, means at

one side of the table for closing the adjacent ends of the channels, and a manifold carried at the opposite side of the table and with which the opposite ends of the channels communicate.

3. In apparatus for use in the surfacing of sheet glass, a table, a mixture of sand and water covering the top of the table to form a semi-solid bed upon which a glass sheet is adapted to be placed, and means for draining off the water from said mixture thereby causing the sand to solidify and secure the sheet upon said table.

4. In apparatus for use in the surfacing of sheet glass, a table provided with a plurality of openings, a covering for the top of the table, and a mixture of sand and water upon said covering to form a semi-solid bed upon which a glass sheet is adapted to be placed, the water in said mixture being caused to pass through the covering and openings thereby causing the sand to solidify and secure the sheet upon said table.

5. In apparatus for use in the surfacing of sheet glass, a table provided with a plurality of channels communicating with the top thereof, a covering for the top of the table, and a mixture of sand and water upon said covering to form a semi-solid bed upon which a glass sheet is adapted to be placed, the water in said mixture passing through the covering into said channels thereby causing the sand to solidify and secure the sheet upon said table.

6. In apparatus for use in the surfacing of sheet glass, a table provided with a plurality of spaced channels communicating with the top thereof and being closed at one end, a manifold carried by the table and with which the opposite ends of the channels communicate, a covering for the top of the table, a mixture of sand and water upon said covering forming a semi-solid bed upon which a glass sheet is adapted to be placed, the water in said mixture passing through the covering into said channels and exteriorly thereof through the manifold thereby causing the sand to solidify and secure the sheet upon said table.

7. In apparatus for use in the surfacing of sheet glass, a table provided with a plurality of channels and a plurality of openings communicating with the channels, a covering for the top of the table, and a mixture of sand and water upon said covering forming a semi-solid bed upon which a glass sheet is adapted to be placed, the water in said mixture passing through the covering and openings into the channels thereby causing the sand to solidify and secure the sheet upon said table.

8. In apparatus for use in the surfacing of sheet glass, a table provided with a plurality of spaced channels and a plurality of openings above and in communication with

the channels, said channels being closed at one end, a manifold carried by the table and with which the opposite ends of said channels communicate, a covering for the top of the table, and a mixture of sand and water upon said covering forming a semi-solid bed upon which a glass sheet is adapted to be placed, the water in said mixture passing through the covering and openings into said channels and exteriorly thereof through the manifold thereby causing the sand to solidify and secure the sheet upon said table.

9. In apparatus for use in the surfacing of sheet glass, a table including a body portion provided with a plurality of channels, a top carried by the body portion and provided with a plurality of openings communicating with said channels, a cover for said top, and a mixture of sand and water upon said covering forming a semi-solid bed upon which a glass sheet is adapted to be placed, the water in said mixture passing through the covering and openings into said channels thereby causing the sand to solidify and secure the sheet upon said table.

10. In apparatus for use in the surfacing of sheet glass, a table including a body portion provided with a plurality of spaced transversely arranged channels closed at one end, a manifold carried by the table and with which the opposite ends of the channels communicate, a top for the body portion provided with a plurality of openings communicating with the channels, a covering for said top, and a mixture of sand and water upon said covering forming a semi-solid bed upon which a glass sheet is adapted to be placed, the water in said mixture passing through the cover and openings into said channels and exteriorly thereof through the manifold thereby causing the sand to solidify and secure the sheet upon said table.

11. The method of bedding glass sheets upon the top of a table, which consists in first depositing upon said table a mixture of sand and water to form a semi-solid bed, laying a sheet upon said bed, and in then removing the water from said mixture thereby causing the sand to solidify and secure the sheet upon said table.

12. The method of bedding glass sheets upon the top of a table, which consists in first depositing upon said table a mixture of sand and water to form a semi-solid bed, laying a sheet upon said bed, and in then causing the water to flow by gravity from said mixture whereby to effect a solidifying of the sand and a consequent securing of the sheet upon said table.

60 Signed at Toledo, in the county of Lucas and State of Ohio, this 23rd day of July, 1928.

DANIEL ADAMS.
